UNITED STATES PATENT OFFICE.

BENJAMIN ABRAHAMS, OF NEW YORK, N. Y.

IMPROVEMENT IN HOUSE VENTILATION.

Specification forming part of Letters Patent No. 174,173, dated February 29, 1876; application filed February 12, 1876.

To all whom it may concern:

Be it known that I, BENJAMIN ABRAHAMS, of New York city, N. Y., have invented certain new and useful Improvements in House Ventilation, of which the following is a specification:

My invention is directed to preventing sewer-gases from entering houses, factories, &c., through the service-pipes which connect the house waste or discharge pipes with the sewer. This I accomplish by providing means whereby the service-pipe is continually ventilated, as is also the street-sewer, and free vent is afforded any gases that might otherwise force their way up through the house-connections into the interior of the building.

It has heretofore been proposed to provide for escape of the sewer-gas by means of a single pipe leading from the service-pipe to the roof of the house. This, however, is practically inoperative, because, when the gases or vapors arising from decomposition, or from flow of hot water in the pipe, rise in the vent-pipe, they tend to create a vacuum in the service-pipe, and this tendency to vacuum of course serves to retain the gases in the service-pipe.

Under my invention I make use of two pipes, through one of which air will enter to replace the gases that may escape through the other. I thus keep the house sewer or service pipe constantly ventilated, and afford opportunity at any and all times for escape of any gases or vapors.

The accompanying drawing represents the manner in which my invention is or may be carried into effect.

A is the inclined service-pipe or house-sewer, that conducts the house-sewage to the main sewer. a a, &c., are the several discharge-connections that conduct the waste from the house into the service-pipe A. B and C are the two pipes by which the house-sewer is ventilated and the gases from the sewer are permitted to escape. The pipe B extends from sewer-pipe A (connecting therewith at a

point just as it enters the house) to the roof of the house, or some feet above it, running for this purpose along the front of the house or inside the wall, or carried by a bend to the rear, or arranged in any other suitable way to reach the roof, or a number of feet above it. Its upper end is, of course, open. The pipe C opens into the sewer-pipe A on the side of the connections a opposite that on which the pipe B enters A, and it extends also to the roof. Pipe C can be used, also, as the rain-spout or waste-pipe that carries the waste from the roof into the sewer.

Under this arrangement the gases generated in or finding their way into the sewer will escape through the vent-pipe B, while a counter-current of air, to supply the displaced air or gases, will pass down pipe C into the sewer; or, vice versa, if the ventilation be effected through the pipe C, a counter or downward current of air will pass through B. In this way there will be a continual ventilation of the sewer, and the gases as fast as they enter or are generated in the service-pipe will be discharged through the pipe B.

Having described my invention, what I claim, and desire to secure by Letters Patent, is—

The method herein described of ventilating house-sewers, and also the sewer in the street, and providing for the discharge of gases generated or entering therein by the employment, in connection with the house sewer or service pipe, of two pipes extending from the sewer-pipe to or above the roof of the building, and arranged so that the gases discharged from the sewer through the one will be replaced by air entering the sewer through the other, substantially as and for the purposes set forth.

In testimony whereof I have hereunto signed my name this 9th day of February, A. D. 1876.

BENJAMIN ABRAHAMS.
